(57) **ABSTRACT**

A display module and a driving method thereof, and a display device are provided. The display module includes a backlight structure including a plurality of backlight partitions. The display module includes a first display mode and a second display mode. Resolution of the display module in the first display mode is greater than the resolution of the display module in the second display mode. In the first display mode, a quantity of the plurality of backlight partitions of the backlight structure is n_1 , and an area of one of the plurality of backlight partitions of the backlight structure is S_1 . In the second display mode, the quantity of the plurality of backlight partitions of the backlight structure is n_2 , and the area of one of the plurality of backlight partitions of the backlight structure is S_2 , with $n_1 > n_2$, and $S_1 < S_2$.

DISPLAY MODULE AND DRIVING METHOD THEREOF, AND DISPLAY DEVICE

CROSS-REFERENCE TO RELATED APPLICATION

This application claims priority of Chinese Patent Application No. 202211634144.3, filed on Dec. 19, 2022, the entire content of which is hereby incorporated by reference.

FIELD OF THE DISCLOSURE

The present disclosure generally relates to the field of display technology and, more particularly, relates to a display module, a driving method thereof, and a display device.

BACKGROUND

In existing technologies, a display module may include a display panel and a backlight module. Brightness of the backlight module may be adjusted by a local dimming technology. The backlight module may be divided into a plurality of backlight partitions, and backlight brightness of each backlight partition may be adjusted separately. When the display module displays a high-resolution picture, and when an area of each backlight partition in the backlight module is large, due to lighting of the backlight partition with a large area, light sources may exist at the edge of the picture that do not need light sources. Since this part of the light source may have a large area, halos may appear at the edge of the picture displayed. That is, dimming effects of the local dimming technology may not be ideal at the position of the backlight module corresponding to the edge of the picture displayed. Tuning of the corresponding display fineness may be difficult, and unfavorable display effects, such as halos at corners of the picture, may appear.

SUMMARY

One aspect of the present disclosure includes a display module. The display module includes a backlight structure including a plurality of backlight partitions. The display module includes a first display mode and a second display mode. Resolution of the display module in the first display mode is greater than the resolution of the display module in the second display mode. In the first display mode, a quantity of the plurality of backlight partitions of the backlight structure is n_1 , and an area of one of the plurality of backlight partitions of the backlight structure is S_1 . In the second display mode, the quantity of the plurality of backlight partitions of the backlight structure is n_2 , and the area of one of the plurality of backlight partitions of the backlight structure is S_2 , with $n_1 > n_2$, and $S_1 < S_2$.

Another aspect of the present disclosure includes a driving method for a display module. The display module includes a backlight structure including a plurality of backlight partitions, the display module includes a first display mode and a second display mode, and resolution of the display module in the first display mode is greater than the resolution of the display module in the second display mode. The driving method includes, in the first display mode, adjusting the backlight partitions of the backlight structure, such that a quantity of the backlight partitions of the backlight structure is n_1 , and an area of one of the backlight partitions of the backlight structure is S_1 . The driving method also includes, in the second display mode, adjusting the backlight partitions of the backlight structure, such that

the backlight partitions of the backlight structure is n_2 , and the area of one of the backlight partitions of the backlight structure is S_2 , with $n_1 > n_2$, and $S_1 < S_2$.

Another aspect of the present disclosure includes a display device. The display device includes a display module. The display module includes a backlight structure including a plurality of backlight partitions. The display module includes a first display mode and a second display mode. Resolution of the display module in the first display mode is greater than the resolution of the display module in the second display mode. In the first display mode, a quantity of the plurality of backlight partitions of the backlight structure is n_1 , and an area of one of the plurality of backlight partitions of the backlight structure is S_1 . In the second display mode, the quantity of the plurality of backlight partitions of the backlight structure is n_2 , and the area of one of the plurality of backlight partitions of the backlight structure is S_2 , with $n_1 > n_2$, and $S_1 < S_2$.

Other aspects of the present disclosure may be understood by those skilled in the art in light of the description, the claims, and the drawings of the present disclosure.

BRIEF DESCRIPTION OF THE DRAWINGS

The following drawings are merely examples for illustrative purposes according to various disclosed embodiments and are not intended to limit the scope of the present disclosure.

FIG. 1 illustrates a schematic structural diagram of a display module consistent with the disclosed embodiments of the present disclosure;

FIG. 2 illustrates a schematic plan view of a backlight structure consistent with the disclosed embodiments of the present disclosure;

FIG. 3 illustrates a schematic partition diagram of the backlight structure in a first display mode, consistent with the disclosed embodiments of the present disclosure;

FIG. 4 illustrates a schematic partition diagram of the backlight structure in a second display mode, consistent with the disclosed embodiments of the present disclosure;

FIG. 5 illustrates a lighting diagram of the backlight structure in a second display mode, consistent with the disclosed embodiments of the present disclosure;

FIG. 6 illustrates a schematic structural diagram of the backlight structure consistent with the disclosed embodiments of the present disclosure;

FIG. 7 illustrates a timing diagram of the backlight structure in the first display mode, consistent with the disclosed embodiments of the present disclosure;

FIG. 8 illustrates a timing diagram of the backlight structure in the second display mode, consistent with the disclosed embodiments of the present disclosure;

FIG. 9 illustrates another lighting diagram of the backlight structure in the second display mode, consistent with the disclosed embodiments of the present disclosure;

FIG. 10 illustrates another timing diagram of the backlight structure in the second display mode, consistent with the disclosed embodiments of the present disclosure;

FIG. 11 illustrates another lighting diagram of the backlight structure in the second display mode, consistent with the disclosed embodiments of the present disclosure;

FIG. 12 illustrates another timing diagram of the backlight structure in the second display mode, consistent with the disclosed embodiments of the present disclosure;

FIG. 13 illustrates another timing diagram of the backlight structure in the second display mode, consistent with the disclosed embodiments of the present disclosure;

FIG. 14 illustrates another lighting diagram of the backlight structure in the second display mode, consistent with the disclosed embodiments of the present disclosure;

FIG. 15 illustrates another structural schematic diagram of the backlight structure consistent with the disclosed embodiments of the present disclosure;

FIG. 16 illustrates another timing diagram of the backlight structure in the second display mode, consistent with the disclosed embodiments of the present disclosure;

FIG. 17 illustrates another lighting diagram of the backlight structure in the second display mode, consistent with the disclosed embodiments of the present disclosure;

FIG. 18 illustrates another timing diagram of the backlight structure in the second display mode, consistent with the disclosed embodiments of the present disclosure;

FIG. 19 illustrates another lighting diagram of the backlight structure in the second display mode, consistent with the disclosed embodiments of the present disclosure;

FIG. 20 illustrates another timing diagram of the backlight structure in the second display mode, consistent with the disclosed embodiments of the present disclosure;

FIG. 21 illustrates another lighting diagram of the backlight structure in the second display mode, consistent with the disclosed embodiments of the present disclosure;

FIG. 22 illustrates another timing diagram of the backlight structure in the second display mode, consistent with the disclosed embodiments of the present disclosure; and

FIG. 23 illustrates a schematic plan view of a display device consistent with the disclosed embodiments of the present disclosure.

DETAILED DESCRIPTION

To make the objectives, technical solutions and advantages of the present disclosure clearer and more explicit, the present disclosure is described in further detail with accompanying drawings and embodiments. It should be understood that the specific exemplary embodiments described herein are only for explaining the present disclosure and are not intended to limit the present disclosure.

Technologies, methods, and equipment known to those of ordinary skill in relevant fields may not be discussed in detail, but where appropriate, these technologies, methods, and equipment should be regarded as part of the specification.

In the present disclosure, any specific values should be construed as exemplary only, and not as limitations. Different embodiments may have different values.

Reference will now be made in detail to embodiments of the present disclosure, which are illustrated in the accompanying drawings. Similar labels and letters designate similar items in the drawings. Once an item is defined in one drawing, the item may not be defined and discussed in subsequent drawings.

FIG. 1 illustrates a schematic structural diagram of a display module consistent with the disclosed embodiments of the present disclosure. FIG. 2 illustrates a schematic plan view of a backlight structure consistent with the disclosed embodiments of the present disclosure. FIG. 3 illustrates a schematic partition diagram of the backlight structure in a first display mode. FIG. 4 illustrates a schematic partition diagram of the backlight structure in a second display mode. With reference to FIGS. 1-4, the present disclosure provides a display module. The display module includes a backlight structure 10. The display module also includes a display panel 20, and the backlight structure 10 is arranged opposite to the display panel 20. The display panel 20 is located on

a light-exiting surface of the backlight structure 10, and the backlight structure 10 provides a light source for the display panel 20. The backlight structure 10 may include a plurality of backlight partitions 11. That is, the backlight structure 10 may be divided into a plurality of backlight partitions 11.

The display module may include a first display mode and a second display mode. Resolution of the display module in the first display mode is greater than resolution of the display module in the second display mode. That is, in the first display mode, the display module may display a high-resolution picture, and in the second display mode, the display module may display a low-resolution picture.

In the first display mode, the quantity of backlight partitions 11a of the backlight structure 10 is n1, and the area of each backlight partition 11a of the backlight structure 10 is S1. In the second display mode, the quantity of backlight partitions 11b of the backlight structure 10 is n2, and the area of each backlight partition 11b of the backlight structure 10 is S2, with n1>n2, S1<S2. That is, the quantity of backlight partitions 11a in the backlight structure 10 in the first display mode is greater than the quantity of backlight partitions 11b in the backlight structure 10 in the second display mode. Accordingly, the area of each backlight partition 11a in the first display mode is smaller than the area of each backlight partition 11a in the second display mode.

Specifically, in the present disclosure, the area of the backlight partition 11 in the backlight structure 10 may be adjusted according to the display mode of the display module. When the display module displays a high-resolution picture, the backlight structure 10 may be divided into more backlight partitions 11, and thus the area of each backlight partition 11 in the backlight structure 10 may be reduced. Accordingly, at the edge of the picture displayed by the display module, the area of the backlight partition 11 may be relatively small. As such, at the edge of the picture displayed, even if a light source may exist at the part that does not need to a light source, the area of the part of the light source may be small. Thus, the halos at the edge of the picture displayed may be reduced, and may even be negligible. Accordingly, the difficulty of adjusting the fineness of high-resolution pictures may be decreased, problems such as halos on the edges of pictures displayed may be reduced, and display effects may thus be improved.

It should be noted that, FIG. 3 exemplarily shows that the backlight structure 10 includes 5×10 backlight partitions 11 in the first display mode, and FIG. 4 exemplarily shows that the backlight structure 10 includes 5×5 backlight partitions 11 in the second display mode. The number, shape and size of the backlight partitions 11 shown in FIG. 3 and FIG. 4 are only schematic illustrations, and do not represent the actual number, shape and size.

FIGS. 3 and 4 exemplarily show that the display module may include a first display mode and a second display mode. In some other embodiments of the present disclosure, the display module may also include other display modes. The area of the backlight partitions 11 in the backlight structure 10 may be adjusted according to the display mode of the display module. When the display module displays a high-resolution picture, the area of each backlight partition 11 in the backlight structure 10 may be reduced. When the display module displays a low-resolution picture, the area of each backlight partition 11 in the backlight structure 10 may be increased.

It should be noted that, FIG. 1 only shows a relative positional relationship between the backlight structure 10 and the display panel 20. FIG. 1 does not illustrate film

structures and sizes of the film structures that may be included in the backlight structure **10** and the display panel **20**.

With continuous reference to FIGS. 1-4, in some embodiments, the backlight structure **10** may include a substrate **12** and a plurality of light-emitting units **13** located on one side of the substrate **12**. Optionally, the light-emitting unit **13** may be a mini light-emitting diode (mini-LED). When the mini-LED is used as a surface light source in the backlight structure **10**, the backlight structure **10** may not need structures such as light guide plates and reflectors. Accordingly, the thickness of the backlight structure **10** may be reduced.

It should be noted that, in some other embodiments, the light-emitting unit **13** may also be an LED or a Micro-LED. The present disclosure will not go into details here.

In the first display mode, the quantity of the light-emitting units **13** in one backlight partition **11a** is N1. In the second display mode, the quantity of the light-emitting units **13** in one backlight partition **11b** is N2, with N1<N2. Exemplarily, referring to FIG. 3, in the first display mode, the quantity of the light-emitting units **13** in the backlight partition **11a** of the backlight structure **10** is 2×1. Referring to FIG. 4, in the second display mode, the quantity of the light-emitting units **13** in the backlight partition **11b** of the backlight structure **10** is 2×2. That is, the quantity of the light-emitting units **13** in the backlight partition **11a** of the backlight structure **10** in the first display mode is smaller than the quantity of the light-emitting units **13** in the backlight partition **11b** of the backlight structure **10** in the second display mode. Accordingly, the area of each backlight partition **11a** in the first display mode is smaller than the area of each backlight partition **11b** in the second display mode.

Specifically, in the display module provided by the present disclosure, the area of the backlight partition **11** in the backlight structure **10** may be adjusted according to the display mode of the display module. When the display module displays a high-resolution picture, the quantity of the light-emitting units **13** in each backlight partition **11** in the backlight structure **10** may be reduced. Accordingly, the area of each backlight partition **11** in the backlight structure **10** may be decreased. As such, the difficulty of adjusting the fineness of the high-resolution picture may be reduced, problems such as halos at the edge of the picture displayed may be alleviated, and the display effect may thus be improved.

It should be noted that FIGS. 2-4 exemplarily show that the backlight structure **10** includes 10×10 light-emitting units **13**. The number, shape and size of the light-emitting units **13** in the backlight structure **10** shown in FIGS. 2-4 are only schematic illustrations, and do not represent the actual number, shape and size. FIG. 3 exemplarily shows that, in the first display mode, the quantity of the light-emitting units **13** in the backlight partition **11a** is 2×1. FIG. 4 exemplarily shows that, in the second display mode, the quantity of the light-emitting units **13** in the backlight sub-region **11b** is 2×2. In some other embodiments, in the first display mode and the second display mode, other numbers of light-emitting units **13** may also be set in the backlight partition **11**. The display module may also include other display modes. The quantity of the light-emitting units **13** in the backlight partition **11** in the backlight structure **10** may be adjusted according to the display mode of the display module. When the display module displays a high-resolution picture, the area of each backlight partition **11** in the backlight structure **10** may be decreased. When the display

module displays a low-resolution picture, the area of each backlight partition **11** in the backlight structure **10** may be increased.

In some embodiments, in the second display mode, some light-emitting units in the backlight partition may not emit light. FIG. 5 illustrates a lighting diagram of the backlight structure in a second display mode. With reference to FIG. 5, in the second display mode, when the backlight partition **11b** in the backlight structure **10** needs to provide a light source, the light-emitting units **13a** may be used to emit light, and the light-emitting units **13b** may not be used to emit light.

Specifically, in one embodiment, the area of the backlight partition **11** in the backlight structure **10** may be adjusted according to the display mode of the display module. When the display module displays a high-resolution picture, the quantity of the light-emitting units **13** in each backlight partition **11** in the backlight structure **10** may be reduced, and the area of each backlight partition **11** in the backlight structure **10** may thus be reduced. Accordingly, the difficulty of adjusting the fineness of the high-resolution picture may be reduced, problems such as halos at the edge of the picture displayed may be alleviated, and the display effect may thus be improved. In addition, in the second display mode, the display module displays a low-resolution picture. When the backlight partition **11b** in the backlight structure **10** needs to provide a light source, some light-emitting units **13** in the backlight partition **11b** may not emit light. As such, while meeting the resolution requirement of the display screen of the display module, power consumption may be reduced, and device consumption may also be reduced.

It should be noted that, FIG. 5 exemplarily shows a distribution diagram of the light-emitting units **13a** used for emitting light and the light-emitting units **13b** not used for emitting light in each backlight partition **11** in the backlight structure **10** in the second display mode. In some other embodiments, in the second display mode, the number and distribution of the light-emitting units **13a** used for emitting light and the light-emitting units **13b** not used for emitting light in each backlight partition **11** of the backlight structure **10** may be set according to actual needs.

FIG. 6 illustrates a structural schematic diagram of the backlight structure consistent with the disclosed embodiments of the present disclosure. With reference to FIGS. 3, 4, and 6, in some embodiments, the plurality of light-emitting units **13** may be arranged in an array along a first direction X and a second direction Y. The first direction X and the second direction Y intersect. Optionally, the first direction X and the second direction Y are perpendicular to each other.

The backlight structure **10** may further include a plurality of scan lines **G** extending along the first direction X and a plurality of data lines **D** extending along the second direction Y. The light-emitting units **13** arranged along the first direction X are electrically connected to a same scan line **G**. That is, an entire row of light-emitting units **13** arranged along the first direction X is electrically connected to a same scan line **G**. The light-emitting units **13** arranged along the second direction Y are electrically connected to a same data line **D**. That is, the entire column of light-emitting units **13** arranged along the second direction Y is electrically connected to a same data line **D**.

The data lines **D** may be used to transmit signals to adjust the quantity of the light-emitting units **13** in each backlight partition **11** in the first display mode and in the second display mode. The scan lines **G** may be used to transmit

signals to adjust the quantity of the light-emitting units **13** in each backlight partition **11** in the first display mode and in the second display mode.

Specifically, FIG. 7 illustrates a timing diagram of the backlight structure in the first display mode, and FIG. 8 illustrates a timing diagram of the backlight structure in the second display mode. Exemplarily, referring to FIGS. 6 and 7, in the first display mode, enable signals are provided to each scan line G sequentially row by row, and the time for providing the enable signals to the scan lines G is staggered from each other. Each data line D is individually controlled. In this case, the quantity of the light-emitting units **13** in each backlight partition in the backlight structure **10** shown in FIG. 6 is one. Referring to FIGS. 6 and 8, in the second display mode, enable signals are provided to each scan line G sequentially row by row, and the time for providing enable signals to the scan lines G is staggered from each other. From the first data line D to the last data line D, the signals of every two data lines D are same. Exemplarily, the signals of the first data line D and the second data line D are same, the signals of the third data line D and the fourth data line D are same, and so on. In this case, the quantity of the light-emitting units **13** in each backlight partition in the backlight structure **10** shown in FIG. 6 is 2x2. That is, the quantity of the light-emitting units **11** in each backlight partition may be adjusted through the signals of the data lines D and/or the scan lines G in the first display mode and in the second display mode.

It should be noted that FIG. 7 exemplarily shows a timing sequence of the backlight structure in the first display mode, and FIG. 8 exemplarily shows a timing sequence of the backlight structure in the second display mode. In some other embodiments, the timing of the backlight structure in the first display mode and the second display mode may be set according to the quantity of the light-emitting units **11** in the backlight partition.

In some embodiments, the data lines may be used to transmit signals to adjust the ratio of the light-emitting units used for emitting light and the light-emitting units not used for emitting light in the backlight partition in the second display mode. The scan lines may also be used to transmit signals to adjust the ratio of the light-emitting units used for emitting light and the light-emitting units not used for emitting light in the backlight partition in the second display mode.

Specifically, FIG. 9 illustrates another lighting diagram of the backlight structure in the second display mode, consistent with the disclosed embodiments of the present disclosure. In the drawings of the present disclosure, as shown in FIG. 8, the filled part in the signal of the data line indicates that the signal to the data line at this time makes the corresponding light-emitting unit not emit light, or, at this time, no signal is provided to the data line such that the corresponding light-emitting unit does not emit light. Exemplarily, referring to FIGS. 8 and 9, in the second display mode, the enable signals are provided to each scan line G sequentially row by row, and the time to provide the enable signals to the scan line G is staggered from each other. From the first data line D to the last data line D, the signals of every two data lines D are same, such that the quantity of the light-emitting units **13** in each backlight partition **11b** in the backlight structure **10** is 2x2. In addition, through the adjustment of the signal on each data line D, in the second display mode, the light-emitting units **13a** used for emitting light in each backlight partition **11b** in the backlight structure **10** may be arranged along the first direction X, and the

light-emitting units **13b** not used for emitting light may be arranged along the first direction X.

Optionally, in the second display mode, in two adjacent backlight partitions **11b** along the first direction X, the light-emitting units **13a** used for emitting light and the light-emitting units **13b** not used for emitting light may be arranged alternately. As such, the overall uniformity of the light source of the backlight structure **10** may be improved, and the display effect may thus be improved.

FIG. 10 illustrates another timing diagram of the backlight structure in the second display mode. FIG. 11 illustrates another lighting diagram of the backlight structure in the second display mode. Referring to FIGS. 10 and 11, in the second display mode, enable signals are provided to each scan line G sequentially row by row, and the time of providing enable signals to the scan lines G is staggered from each other. Each data line D is controlled independently. Accordingly, the quantity of the light-emitting units **13** in each backlight partition **11b** in the backlight structure **10** is 2x2. In addition, through the adjustment of the signal on each data line D, in the second display mode, the light-emitting units **13a** used for emitting light in each backlight partition **11b** in the backlight structure **10** may be arranged along the second direction Y, and the light-emitting units **13b** not used for emitting light may be arranged along the second direction Y.

Optionally, in the second display mode, in two adjacent backlight partitions **11b** along the second direction Y, the light-emitting units **13a** used for emitting light and the light-emitting units **13b** not used for emitting light may be arranged alternately. As such, the overall uniformity of the light source of the backlight structure **10** may be improved, and thus the display effect may be improved.

FIG. 12 illustrates another timing diagram of the backlight structure in the second display mode, consistent with the disclosed embodiments of the present disclosure. Referring to FIGS. 11 and 12, in the second display mode, from the first scan line G to the last scan line G, every two scan lines G in a same scan line group are same. The enable signals are sequentially provided to the scan lines G in each scan line group, and the time for providing the enable signals to the scan lines G in each scan line group is staggered from each other. Each data line D is controlled independently. As such, the quantity of the light-emitting units **13** in each backlight partition **11b** in the backlight structure **10** is also 2x2. In addition, through the adjustment of the signal on each data line D, in the second display mode, the light-emitting units **13a** used for emitting light in each backlight partition **11b** in the backlight structure **10** may be arranged along the second direction Y, and the light-emitting units **13b** not used for emitting light may be arranged along the second direction Y.

FIG. 13 illustrates another timing diagram of the backlight structure in the second display mode, consistent with the disclosed embodiments of the present disclosure. FIG. 14 illustrates another lighting diagram of the backlight structure in the second display mode, consistent with the disclosed embodiments of the present disclosure. Referring to FIGS. 13 and 14, in the second display mode, enable signals are provided to each scan line G sequentially row by row, and the time of providing enable signals to scan lines G is staggered from each other. Each data line D is controlled independently. Accordingly, the quantity of the light-emitting units **13** in each backlight partition **11b** in the backlight structure **10** is also 2x2. In addition, through the adjustment of the signal on each data line D, in the second display mode, in the backlight structure **10**, the light-

emitting units **13a** used for emitting light and the light-emitting units **13b** not used for emitting light in each backlight partition **11b** may be alternately arranged in the first direction X and the second direction Y.

In the second display mode, the ratio of the light-emitting unit **13a** used for emitting light to the light-emitting unit **13b** not used for emitting light in the backlight partition **11b** may be adjusted through the signals of the data lines D and/or the scan lines G. In addition, the arrangement of the light-emitting units **13a** used for emitting light and the light-emitting units **13b** not used for emitting light in the backlight partition **11b** may be adjusted through the signals of the data lines D and/or the scan lines G.

It should be noted that, in the present disclosure, in the second display mode, when the quantity of the light-emitting units **13** in each backlight partition **11b** in the backlight structure **10** is 2×2 , a plurality of arrangements of the light-emitting units **13a** used for emitting light and the light-emitting units **13b** not used for emitting light in the backlight partition **11b** may be achieved through the adjustment of the signals of the data lines D and the scan lines G. In some other embodiments, other signal adjustment methods may also be used. The present disclosure will not go into details here.

In the second display mode, when the numbers of light-emitting units **13** in each backlight partition **11b** in the backlight structure **10** are other numbers, realization of arrangements of the light-emitting units **13a** used for emitting light and the light-emitting units **13b** not used for emitting light in the backlight partition **11b** through the adjustment of signals in the data lines D and the scan lines G may refer to the adjustment of the signals of the data lines D and the scan lines G presented in the present disclosure. The present disclosure will not go into details here.

FIG. 15 illustrates another structural schematic diagram of the backlight structure consistent with the disclosed embodiments of the present disclosure. Referring to FIG. 15, in some embodiments, the backlight structure **10** may further include two or more shift-register groups **14**. Two adjacent scan lines G may be electrically connected to different shift-register groups **14** respectively. That is, adjacent scan lines G may be electrically connected to different shift-register groups **14**.

Referring to FIGS. 11, 12 and 15, in the second display mode, from the first scan line G to the last scan line G, every two scan lines G are a scan line group. The signals of the scan lines G in a same scan line group are same. Enable signals are provided to the scan lines G in each scan line group sequentially, and the time for providing the enable signals to the scan lines G in each scan line group is staggered from each other. Each data line D is controlled independently. Accordingly, the quantity of the light-emitting units **13** in each backlight partition **11b** in the backlight structure **10** is also 2×2 . Furthermore, through the adjustment of the signals on each data line D, in the second display mode, the light-emitting units **13a** used for emitting light in each backlight partition **11b** in the backlight structure **10** may be arranged along the second direction Y, and the light-emitting units **13b** not used for emitting light may be arranged along the second direction Y.

The backlight structure **10** may also include at two or more shift-register groups **14**. Two adjacent scan lines G may be electrically connected to different shift-register groups **14** respectively. That is, the scan lines G in each scan line group may be electrically connected to different shift-register groups **14**. Two shift-register groups **14** may simultaneously provide same signals to different scan lines G in

a same scan line group that are electrically connected to the two shift-register groups **14**. Thus, the signals of the scan lines G in the same scan line group may be same. Accordingly, the difficulty of driving the scan lines G by the shift-register groups **14** may be reduced, the design difficulty of the register groups **14** may be reduced, and the production cost may be decreased.

In one embodiment, the backlight structure **10** includes two shift-register groups **14**. The two shift-register groups **14** are respectively a shift-register group **14a** and a shift-register group **14b**. Adjacent scan lines G are electrically connected to the shift-register group **14a** and the shift-register group **14b** respectively. In some other embodiments, the backlight structure **10** may include other numbers of shift-register groups **14**. The connection methods between the shift-register groups **14** and each scan line G may be set with reference to the present disclosure.

Optionally, a shift-register group **14** may include two gate drive circuits. One scan line G may be electrically connected to the two gate drive circuits. Accordingly, the drive capability of the scan line G may be improved. In some other embodiments, a shift-register group **14** may include one gate driving circuit, and the present disclosure will not go into details here.

The present disclosure also provides a driving method for a display module. With continuous reference to FIGS. 1-4, the display module includes a backlight structure **10**. The display module also includes a display panel **20**, and the backlight structure **10** is arranged opposite to the display panel **20**. The display panel **20** is located on a light-exiting surface of the backlight structure **10**, and the backlight structure **10** provides a light source for the display panel **20**. The backlight structure **10** may include a plurality of backlight partitions **11**. That is, in the backlight structure **10**, the backlight structure **10** may be divided into a plurality of backlight partitions **11**.

The driving method includes:

The display module may have a first display mode and a second display mode. The resolution of the display module in the first display mode is greater than the resolution of the display module in the second display mode. That is, in the first display mode, the display module may display a high-resolution picture, and in the second display mode, the display module may display a low-resolution picture.

In the first display mode, the backlight partitions **11a** of the backlight structure **10** may be adjusted such that the quantity of the backlight partitions **11a** of the backlight structure **10** is n_1 , and the area of the backlight partitions **11a** of the backlight structure **10** is S_1 .

In the second display mode, the backlight partition **11b** of the backlight structure **10** may be adjusted such that the quantity of the backlight partition **11b** of the backlight structure **10** is n_2 , and the area of the backlight partition **11b** of the backlight structure **10** is S_2 , with $n_1 > n_2$, $S_1 < S_2$. That is, the quantity of backlight partitions **11a** of the backlight structure **10** in the first display mode may be greater than the quantity of backlight partitions **11b** of the backlight structure **10** in the second display mode. Accordingly, the area of each backlight partition **11a** in the first display mode may be smaller than the area of each backlight partition **11a** in the second display mode.

Specifically, in the driving method of the display module provided by the present disclosure, the area of the backlight partition **11** in the backlight structure **10** may be adjusted according to the display mode of the display module. When the display module displays a high-resolution picture, the backlight structure **10** may be divided into more backlight

11

partitions **11**, and thus the area of each backlight partition **11** in the backlight structure **10** may be reduced. Accordingly, at the edge of the picture displayed by the display module, the area of the backlight partition **11** may be relatively small. In this case, even if a light source may exist at the edge of the display screen that does not need a light source, the area of the light source in this part may be small. As such, the halos at the edge of the display screen may be alleviated, and may even be negligible. Accordingly, the difficulty of adjusting the fineness of the high-resolution picture may be reduced, problems such as the halos at the edge of the picture displayed may be alleviated, and the display effect may thus be improved.

With continuous reference to FIGS. 1-4, in some embodiments, the backlight structure **10** may include a substrate **12** and a plurality of light-emitting units **13** located on one side of the substrate **12**. Optionally, the light-emitting unit **13** may be a mini light-emitting diode (mini-LED). When the mini-LED is used as a surface light source in the backlight structure **10**, the backlight structure **10** may not need structures such as light guide plates and reflectors. Accordingly, the thickness of the backlight structure **10** may be reduced.

It should be noted that, in some other embodiments, the light-emitting unit **13** may also be an LED or a Micro-LED. The present disclosure will not go into details here.

In the first display mode, the quantity of the light-emitting units **13** in one backlight partition **11a** is N_1 . In the second display mode, the quantity of the light-emitting units **13** in one backlight partition **11b** is N_2 , with $N_1 < N_2$. Exemplarily, referring to FIG. 3, in the first display mode, the quantity of the light-emitting units **13** in the backlight partition **11a** of the backlight structure **10** is 2×1 . Referring to FIG. 4, in the second display mode, the quantity of the light-emitting units **13** in the backlight partition **11b** of the backlight structure **10** is 2×2 . That is, the quantity of the light-emitting units **13** in the backlight partition **11a** of the backlight structure **10** in the first display mode is smaller than the quantity of the light-emitting units **13** in the backlight partition **11b** of the backlight structure **10** in the second display mode. Accordingly, the area of each backlight partition **11a** in the first display mode is smaller than the area of each backlight partition **11b** in the second display mode.

Specifically, in the display module provided by the present disclosure, the area of the backlight partition **11** in the backlight structure **10** may be adjusted according to the display mode of the display module. When the display module displays a high-resolution picture, the quantity of the light-emitting units **13** in each backlight partition **11** in the backlight structure **10** may be reduced. Accordingly, the area of each backlight partition **11** in the backlight structure **10** may be decreased. As such, the difficulty of adjusting the fineness of the high-resolution picture may be reduced, problems such as halos at the edge of the picture displayed may be alleviated, and the display effect may thus be improved.

In some embodiments, in the second display mode, some light-emitting units in the backlight partition may not emit light. FIG. 5 illustrates a lighting diagram of the backlight structure in a second display mode. With reference to FIG. 5, in the second display mode, when the backlight partition **11b** in the backlight structure **10** needs to provide a light source, the light-emitting units **13a** may be used to emit light, and the light-emitting units **13b** may not be used to emit light.

Specifically, in one embodiment, the area of the backlight partition **11** in the backlight structure **10** may be adjusted according to the display mode of the display module. When

12

the display module displays a high-resolution picture, the quantity of the light-emitting units **13** in each backlight partition **11** in the backlight structure **10** may be reduced, and the area of each backlight partition **11** in the backlight structure **10** may thus be reduced. Accordingly, the difficulty of adjusting the fineness of the high-resolution picture may be reduced, problems such as halos at the edge of the picture displayed may be alleviated, and the display effect may thus be improved. In addition, in the second display mode, the display module displays a low-resolution picture. When the backlight partition **11b** in the backlight structure **10** needs to provide a light source, some light-emitting units **13** in the backlight partition **11b** may not emit light. As such, while meeting the resolution requirement of the display screen of the display module, power consumption may be reduced, and device consumption may also be reduced.

With continuous reference to FIGS. 3, 4 and 6, in some embodiments, the plurality of light-emitting units **13** may be arranged in an array along a first direction X and a second direction Y. The first direction X and the second direction Y intersect. Optionally, the first direction X and the second direction Y are perpendicular to each other.

The backlight structure **10** may further include a plurality of scan lines **G** extending along the first direction X and a plurality of data lines **D** extending along the second direction Y. The light-emitting units **13** arranged along the first direction X are electrically connected to a same scan line **G**. That is, an entire row of light-emitting units **13** arranged along the first direction X is electrically connected to a same scan line **G**. The light-emitting units **13** arranged along the second direction Y are electrically connected to a same data line **D**. That is, an entire column of light-emitting units **13** arranged along the second direction Y is electrically connected to a same data line **D**.

The data lines **D** may be used to transmit signals to adjust the quantity of the light-emitting units **13** in each backlight partition **11** in the first display mode and in the second display mode. The scan lines **G** may be used to transmit signals to adjust the quantity of the light-emitting units **13** in each backlight partition **11** in the first display mode and in the second display mode.

Specifically, FIG. 7 illustrates a timing diagram of the backlight structure in the first display mode, and FIG. 8 illustrates a timing diagram of the backlight structure in the second display mode. Exemplarily, referring to FIGS. 6 and 7, in the first display mode, enable signals are provided to each scan line **G** sequentially row by row, and the time for providing the enable signals to the scan lines **G** is staggered from each other. Each data line **D** is individually controlled. In this case, the quantity of the light-emitting units **13** in each backlight partition in the backlight structure **10** shown in FIG. 6 is one. Referring to FIGS. 6 and 8, in the second display mode, enable signals are provided to each scan line **G** sequentially row by row, and the time for providing enable signals to the scan lines **G** is staggered from each other. From the first data line **D** to the last data line **D**, the signals of every two data lines **D** are same. Exemplarily, the signals of the first data line **D** and the second data line **D** are same, the signals of the third data line **D** and the fourth data line **D** are the same, and so on. In this case, the quantity of the light-emitting units **13** in each backlight partition in the backlight structure **10** shown in FIG. 6 is 2×2 . That is, the quantity of the light-emitting units **11** in each backlight partition may be adjusted through the signals of the data lines **D** and/or the scan lines **G** in the first display mode and in the second display mode.

13

In some embodiments, in the second display mode, the ratio of the light-emitting units used for emitting light and the light-emitting units not used for emitting light in the backlight partition may be adjusted by the signals of the data lines and/or the scan lines.

Specifically, with continuous reference to FIGS. 8 and 9, in the second display mode, enable signals are provided to each scan line G sequentially row by row, and the time to provide the enable signals to the scan line G is staggered from each other. From the first data line D to the last data line D, the signals of every two data lines D are same, such that the quantity of the light-emitting units 13 in each backlight partition 11b in the backlight structure 10 is 2×2. In addition, through the adjustment of the signal on each data line D, in the second display mode, the light-emitting units 13a used for emitting light in each backlight partition 11b in the backlight structure 10 may be arranged along the first direction X, and the light-emitting units 13b not used for emitting light may be arranged along the first direction X.

With continuous reference to FIGS. 10 and 11, in the second display mode, the enable signals are provided to each scan line G sequentially row by row, and the time to provide the enable signals to the scan line G is staggered from each other. From the first data line D to the last data line D, the signals of every two data lines D are same, such that the quantity of the light-emitting units 13 in each backlight partition 11b in the backlight structure 10 is 2×2. In addition, through the adjustment of the signal on each data line D, in the second display mode, the light-emitting units 13a used for emitting light in each backlight partition 11b in the backlight structure 10 may be arranged along the second direction Y, and the light-emitting units 13b not used for emitting light may be arranged along the second direction Y.

With continuous reference to FIGS. 11 and 12, in the second display mode, from the first scan line G to the last scan line G, every two scan lines G are a scan line group. The signals of the scan lines G in a same scan line group are same. Enable signals are provided to the scan lines G in each scan line group sequentially, and the time for providing the enable signals to the scan lines G in each scan line group is staggered from each other. Each data line D is controlled independently. Accordingly, the quantity of the light-emitting units 13 in each backlight partition 11b in the backlight structure 10 is also 2×2. Furthermore, through the adjustment of the signals on each data line D, in the second display mode, the light-emitting units 13a used for emitting light in each backlight partition 11b in the backlight structure 10 may be arranged along the second direction Y, and the light-emitting units 13b not used for emitting light may be arranged along the second direction Y.

With continuous reference to FIGS. 13 and 4, in the second display mode, enable signals are provided to each scan line G sequentially row by row, and the time of providing enable signals to scan lines G is staggered from each other. Each data line D is controlled independently. Accordingly, the quantity of the light-emitting units 13 in each backlight partition 11b in the backlight structure 10 is also 2×2. In addition, through the adjustment of the signal on each data line D, in the second display mode, in the backlight structure 10, the light-emitting units 13a used for emitting light and the light-emitting units 13b not used for emitting light in each backlight partition 11b may be alternately arranged in the first direction X and the second direction Y.

FIGS. 7-14 exemplarily show the realization of a plurality of arrangements of the light-emitting units 13a used for emitting light and the light-emitting units 13b not used for

14

emitting light in the backlight partition 11b through the adjustment of the signals of the data lines D and the scan lines G, when the quantity of the light-emitting units 13 in each backlight partition 11b in the backlight structure 10 is 2×2, in the second display mode.

FIG. 16 illustrates another timing diagram of the backlight structure in the second display mode, consistent with the disclosed embodiments of the present disclosure. FIG. 17 illustrates another lighting diagram of the backlight structure in the second display mode, consistent with the disclosed embodiments of the present disclosure. Referring to FIGS. 16 and 17, enable signals are provided to the scan lines G sequentially row by row, and the time of providing the enable signals to the scan lines G are staggered from each other. From the first data line D to the last data line D, the signals of every three data lines D are same, such that the quantity of the light-emitting units 13 in each backlight partition 11b in the backlight structure 10 is 3×2. In addition, through the adjustment of the signal on each data line D, in the second display mode, the light-emitting units 13a used for emitting light in each backlight partition 11b in the backlight structure 10 may be arranged along the first direction X, and the light-emitting units 13b not used for emitting light in each backlight partition 11b in the backlight structure 10 may be arranged along the first direction X.

FIG. 18 illustrates another timing diagram of the backlight structure in the second display mode, consistent with the disclosed embodiments of the present disclosure. FIG. 19 illustrates another lighting diagram of the backlight structure in the second display mode, consistent with the disclosed embodiments of the present disclosure. Referring to FIGS. 18 and 19, enable signals are provided to each scan line G sequentially row by row, and each data line D is controlled independently, such that the quantity of the light-emitting units 13 in each backlight partition 11b in the backlight structure 10 is 2×3. In addition, through the adjustment of the signal on each data line D, in the second display mode, the light-emitting units 13a used for emitting light in each backlight partition 11b in the backlight structure 10 may be arranged along the second direction Y, and the light-emitting units 13b not used for emitting light may be arranged along the second direction Y.

FIG. 20 illustrates another timing diagram of the backlight structure in the second display mode, consistent with the disclosed embodiments of the present disclosure. FIG. 21 illustrates another lighting diagram of the backlight structure in the second display mode, consistent with the disclosed embodiments of the present disclosure. Referring to FIGS. 20 and 21, enable signals are provided to the scan lines G sequentially row by row, and the time of providing the enable signals to the scan lines G is staggered from each other. From the first data line D to the last data line D, the signals of every two data lines D are same, such that the quantity of the light-emitting units 13 in each backlight partition 11b in the backlight structure 10 is 4×2. In addition, through the adjustment of the signal on each data line D, in the second display mode, in the backlight structure 10, the light-emitting units 13a used for emitting light in each backlight partition 11b may be arranged in a 2×2 matrix along the first direction X and the second direction Y. The light-emitting units 13b not used for emitting light may also be arranged in a 2×2 matrix along the first direction X and the second direction Y.

FIG. 22 illustrates another timing diagram of the backlight structure in the second display mode, consistent with the disclosed embodiments of the present disclosure. Referring to FIGS. 21 and 22, in the second display mode, from

the first scan line G to the last scan line G, every two scan lines G are a scan line group. The signals of the scan lines G in a same scan line group are same. Enable signals are provided to the scan lines G in each scan line group sequentially. The time to provide the enable signals to the scan lines G in each scan line group is staggered from each other. From the first data line D to the last data line D, the signals of every two data lines D are same, such that the quantity of the light-emitting units 13 in each backlight partition 11b in the backlight structure 10 is 4×2. In addition, through the adjustment of the signal on each data line D, in the second display mode, in the backlight structure 10, the light-emitting units 13a used for emitting light in each backlight partition 11b may be arranged in a 2×2 matrix along the first direction X and the second direction Y. The light-emitting units 13b not used for emitting light may also be arranged in a 2×2 matrix along the first direction X and the second direction Y.

As discussed above, in the second display mode, the ratio of the light-emitting unit 13a used for emitting light to the light-emitting unit 13b not used for emitting light in the backlight partition 11b may be adjusted through the signals of the data lines D and/or the scan lines G. In addition, the arrangement of the light-emitting units 13a used for emitting light and the light-emitting units 13b not used for emitting light in the backlight partition 11b may be adjusted through the signals of the data lines D and/or the scan lines G.

It should be noted that, in the present disclosure, in the second display mode, when the quantity of the light-emitting units 13 in each backlight partition 11b in the backlight structure 10 is 2×2, 3×2, 2×3, or 4×2, a plurality of arrangements of the light-emitting units 13a used for emitting light and the light-emitting units 13b not used for emitting light in the backlight partition 11b may be achieved through the adjustment of the signals of the data lines D and the scan lines G. In some other embodiments, other signal adjustment methods may also be used. The present disclosure will not go into details here.

In the second display mode, when the quantity of light-emitting units 13 in each backlight partition 11b in the backlight structure 10 is another number, realization of arrangements of the light-emitting units 13a used for emitting light and the light-emitting units 13b not used for emitting light in the backlight partition 11b through the adjustment of signals in the data lines D and the scan lines G may refer to the adjustment of the signals of the data lines D and the scan lines G presented in the present disclosure. The present disclosure will not go into details here.

In some embodiments, in the second display mode, among the data lines electrically connected to the light-emitting units in a same backlight partition, two or more data lines have a same signal. Accordingly, in the second display mode, each backlight partition may include a plurality of light-emitting units.

Exemplarily, with continuous reference to FIGS. 8 and 9, in the second display mode, enable signals are provided to each scan line G sequentially row by row, and the time to provide the enable signals to the scan line G is staggered from each other. From the first data line D to the last data line D, the signals of every two data lines D are same, such that the quantity of the light-emitting units 13 in each backlight partition 11b in the backlight structure 10 is 2×2. In addition, through the adjustment of the signal on each data line D, in the second display mode, the light-emitting units 13a used for emitting light in each backlight partition 11b in the backlight structure 10 may be arranged along the first

direction X, and the light-emitting units 13b not used for emitting light may be arranged along the first direction X.

With continuous reference to FIG. 15, in some embodiments, the backlight structure 10 may further include two or more shift-register groups 14. Two adjacent scan lines G may be electrically connected to different shift-register groups 14 respectively. That is, adjacent scan lines G may be electrically connected to different shift-register groups 14.

Since adjacent scan lines G are electrically connected to different shift-register groups 14, in some embodiments, in the second display mode, scan enable signals may be simultaneously provided to two or more scan lines G of the scan lines G electrically connected to the light-emitting units 13 in a same backlight partition 11b through different shift-register groups 14.

Exemplarily, with continuous reference to FIGS. 11, 12 and 15, in the second display mode, from the first scan line G to the last scan line G, every two scan lines G are a scan line group. The signals of the scan lines G in a same scan line group are same. Enable signals are provided to the scan lines G in each scan line group sequentially, and the time for providing the enable signals to the scan lines G in each scan line group is staggered from each other. Each data line D is controlled independently. Accordingly, the quantity of the light-emitting units 13 in each backlight partition 11b in the backlight structure 10 is also 2×2. Furthermore, through the adjustment of the signals on each data line D, in the second display mode, the light-emitting units 13a used for emitting light in each backlight partition 11b in the backlight structure 10 may be arranged along the second direction Y, and the light-emitting units 13b not used for emitting light may be arranged along the second direction Y.

The backlight structure 10 may also include at two or more shift-register groups 14. Two adjacent scan lines G may be electrically connected to different shift-register groups 14 respectively. That is, the scan lines G in each scan line group may be electrically connected to different shift-register groups 14. Two shift-register groups 14 may simultaneously provide same signals to different scan lines G in a same scan line group that are electrically connected to the two shift-register groups 14. Thus, the signals of the scan lines G in the same scan line group may be same. Accordingly, the difficulty of driving the scan lines G by the shift-register groups 14 may be reduced, the design difficulty of the register groups 14 may be reduced, and the production cost may be decreased.

In one embodiment, the backlight structure 10 includes two shift-register groups 14. In some other embodiments, the backlight structure 10 may include other numbers of shift-register groups 14. The connection methods between the shift-register groups 14 and each scan line G may be set with reference to the present disclosure.

FIG. 23 illustrates a schematic plan view of a display device consistent with the disclosed embodiments of the present disclosure. The present disclosure also provides a display device 1000. The display device 1000 includes the display module 100 provided in the present disclosure. FIG. 23 only takes a mobile phone as an example to illustrate the display device 1000. In the present disclosure, the display device 1000 may also be other display devices 1000 with a display function, such as a computer, a television, a vehicle-mounted display device, etc. The present disclosure does not specifically limit types of display devices. The display device 1000 provided by the present disclosure has the beneficial effects of the display module 100 provided by the

17

present disclosure. For details, reference may be made to the specific descriptions of the display module 100 in the present disclosure.

As disclosed, the technical solutions of the present disclosure have the following advantages.

In the display module provided by the present disclosure, the area of the backlight partition in the backlight structure may be adjusted according to the display mode of the display module. When the display module displays a high-resolution picture, the backlight structure may be divided into more backlight partitions, and thus the area of each backlight partition in the backlight structure may be reduced. Accordingly, at the edge of the picture displayed by the display module, the area of the backlight partition may be relatively small. As such, at the edge of the picture displayed, even if a light source may exist at the part that does not need a light source, the area of the part of the light source may be small. Thus, the halos at the edge of the picture displayed may be reduced, and may even be negligible. Accordingly, the difficulty of adjusting the fineness of high-resolution pictures may be decreased, problems such as halos on the edges of pictures displayed may be reduced, and display effects may thus be improved.

The embodiments disclosed herein are exemplary only and not limiting the scope of the present disclosure. Various combinations, alternations, modifications, equivalents, or improvements to the technical solutions of the disclosed embodiments may be obvious to those skilled in the art. Without departing from the spirit and scope of this disclosure, such combinations, alternations, modifications, equivalents, or improvements to the disclosed embodiments are encompassed within the scope of the present disclosure.

What is claimed is:

1. A display module, comprising:
a backlight structure including a plurality of backlight partitions, a substrate, and a plurality of light-emitting units located on one side of the substrate, wherein:
the display module includes a first display mode and a second display mode;
resolution of the display module in the first display mode is greater than the resolution of the display module in the second display mode;
in the first display mode, a quantity of the plurality of backlight partitions of the backlight structure is n_1 , and an area of one of the plurality of backlight partitions of the backlight structure is S_1 ;
2. The display module according to claim 1, wherein in the second display mode, the quantity of the plurality of backlight partitions of the backlight structure is n_2 , and the area of one of the plurality of backlight partitions of the backlight structure is S_2 , with $n_1 > n_2$, and $S_1 < S_2$, and part of light-emitting units in a backlight partition do not emit light and remaining light-emitting units in the same backlight partition emit light in the second display mode;
3. The display module according to claim 1, wherein the plurality of light-emitting units is arranged in an array along a first direction and a second direction, wherein the first direction and the second direction intersect; and
4. The display module according to claim 3, wherein in the second display mode, the light-emitting units used for emitting light and the light-emitting units not used for emitting light are arranged alternately in two adjacent backlight partitions along one of the first direction and the second direction.

18

2. The display module according to claim 1, wherein: in the first display mode, a quantity of the light-emitting units in one of the plurality of backlight partitions is N_1 ; and

3. The display module according to claim 1, wherein: in the second display mode, the quantity of the light-emitting units in one of the plurality of backlight partitions is N_2 , with $N_1 < N_2$.

4. The display module according to claim 1, wherein: the backlight structure further includes a plurality of scan lines extending along the first direction and a plurality of data lines extending along the second direction; the light-emitting units arranged along the first direction are electrically connected to a same scan line, and the light-emitting units arranged along the second direction are electrically connected to a same data line; and the plurality of data lines is used to transmit signals to adjust the quantity of the light-emitting units in each backlight partition in the first display mode and in the second display mode, and/or the plurality of scan lines is used to transmit signals to adjust the quantity of the light-emitting units in each backlight partition in the first display mode and in the second display mode.

5. The display module according to claim 1, wherein: the plurality of data lines is used to transmit signals to adjust a ratio of the light-emitting units used for emitting light and the light-emitting units not used for emitting light in the backlight partition in the second display mode; and/or the plurality of scan lines is used to transmit signals to adjust the ratio of the light-emitting units used for emitting light and the light-emitting units not used for emitting light in the backlight partition in the second display mode.

6. The display module according to claim 3, wherein: the backlight structure further includes two or more shift-register groups; and two adjacent scan lines are electrically connected to different shift-register groups respectively.

7. The display module according to claim 2, wherein: the light-emitting unit includes a mini light-emitting diode (mini-LED).

8. A driving method for a display module, wherein the display module includes a backlight structure including a plurality of backlight partitions, a substrate, and a plurality of light-emitting units located on one side of the substrate, the display module includes a first display mode and a second display mode, and resolution of the display module in the first display mode is greater than the resolution of the display module in the second display mode, comprising:
in the first display mode, adjusting the backlight partitions of the backlight structure, such that a quantity of the backlight partitions of the backlight structure is n_1 , and an area of one of the backlight partitions of the backlight structure is S_1 ;

9. The driving method according to claim 8, wherein in the second display mode, adjusting the backlight partitions of the backlight structure, such that the backlight partitions of the backlight structure is n_2 , and the area of one of the backlight partitions of the backlight structure is S_2 , with $n_1 > n_2$, and $S_1 < S_2$, and controlling part of light-emitting units in a backlight partition not to emit light and remaining light-emitting units in the same backlight partition to emit light;

10. The driving method according to claim 8, wherein in the second display mode, the light-emitting units used for emitting light and the light-emitting units not used for emitting light are arranged alternately in two adjacent backlight partitions along one of the first direction and the second direction;

11. The driving method according to claim 9, wherein in the second display mode, the light-emitting units used for emitting light and the light-emitting units not used for emitting light are arranged alternately in two adjacent backlight partitions along one of the first direction and the second direction.

19

for emitting light are arranged alternately in two adjacent backlight partitions along one of the first direction and the second direction.

8. The driving method according to claim 7, wherein the method further comprises:

in the first display mode, adjusting the backlight partitions of the backlight structure, such that a quantity of the light-emitting units in one of the plurality of backlight partitions is N_1 ; and

in the second display mode, adjusting the backlight partitions of the backlight structure, such that the quantity of the light-emitting units in one of the plurality of backlight partitions is N_2 , with $N_1 < N_2$.

9. The driving method according to claim 7, wherein: the backlight structure further includes a plurality of scan lines extending along the first direction and a plurality of data lines extending along the second direction; the light-emitting units arranged along the first direction are electrically connected to a same scan line, and the light-emitting units arranged along the second direction are electrically connected to a same data line; and the quantities of the light-emitting units in each backlight partition in the first display mode and in the second display mode are adjusted through signals in the data lines and/or the scan lines.

10. The driving method according to claim 9, wherein: in the second display mode, a ratio of the light-emitting units used for emitting light and the light-emitting units not used for emitting light in the backlight partitions is adjusted through the signals in the data lines and/or the scan lines.

11. The driving method according to claim 9, wherein: in the second display mode, among the data lines electrically connected to the light-emitting units in a same backlight partition, two or more of the data lines have a same signal.

12. The driving method according to claim 9, wherein: the backlight structure further includes two or more shift-register groups; and two adjacent scan lines are electrically connected to 40 different shift-register groups respectively.

13. The driving method according to claim 12, wherein: in the second display mode, through different shift-register groups of the shift-register groups, scan enable signals are simultaneously provided to two or more 45 scan lines of the scan lines electrically connected to the light-emitting units in a same backlight partition of the backlight partitions.

14. A display device, comprising a display module, wherein:

the display module comprises a backlight structure including a plurality of backlight partitions, a substrate, and a plurality of light-emitting units located on one side of the substrate,

20

wherein:

the display module includes a first display mode and a second display mode;

resolution of the display module in the first display mode is greater than the resolution of the display module in the second display mode;

in the first display mode, a quantity of the plurality of backlight partitions of the backlight structure is n_1 , and an area of one of the plurality of backlight partitions of the backlight structure is S_1 ;

in the second display mode, the quantity of the plurality of backlight partitions of the backlight structure is n_2 , and the area of one of the plurality of backlight partitions of the backlight structure is S_2 , with $n_1 > n_2$, and $S_1 < S_2$, and part of light-emitting units in a backlight partition do not emit light and remaining light-emitting units in the same backlight partition emit light in the second display mode;

the plurality of light-emitting units is arranged in an array along a first direction and a second direction, wherein the first direction and the second direction intersect; and

in the second display mode, the light-emitting units used for emitting light and the light-emitting units not used for emitting light are arranged alternately in two adjacent backlight partitions along one of the first direction and the second direction.

15. The display module according to claim 1, further comprising a display panel, wherein:

the backlight structure is arranged opposite to the display panel; and

the display panel is located on a light-exiting surface of the backlight structure.

16. The display module according to claim 4, wherein:

in the second display mode, in two adjacent backlight partitions along the first direction, the light-emitting units used for emitting light and the light-emitting units not used for emitting light are arranged alternately.

17. The display module according to claim 4, wherein: in the second display mode, in two adjacent backlight partitions along the second direction, the light-emitting units used for emitting light and the light-emitting units not used for emitting light are arranged alternately.

18. The driving method according to claim 7, wherein: the display module further includes a display panel; the backlight structure is arranged opposite to the display panel; and

the display panel is located on a light-exiting surface of the backlight structure.
